UNITED STATES PATENT OFFICE.

WILLIAM DIETER, OF BROOKLYN, NEW YORK, ASSIGNOR TO E. W. BLISS COMPANY, OF BROOKLYN, NEW YORK, A CORPORATION OF WEST VIRGINIA.

AUTOMOBILE TORPEDO.

1,303,044.

Specification of Letters Patent.

Patented May 6, 1919.

Application filed February 8, 1918. Serial No. 216,102.

To all whom it may concern:

Be it known that I, WILLIAM DIETER, a citizen of the United States of America, residing in the borough of Brooklyn, county 5 of Kings, city and State of New York, have invented certain new and useful Improvements in Automobile Torpedoes, of which the following is a specification.

This invention relates to automobile torpedoes having automatic steering mechanism, such as the well-known gyroscopic steering mechanism. The purpose of the invention is to make provision for interrupting the normal steering after the torpedo has completed a predetermined portion 10 of its normal run and to thereupon cause the torpedo to steer in an approximately circular course.

If, for example, an enemy fleet is at a distance of say 10,000 yards from the torpedo boat from which the torpedo is to be launched, it is desirable to have the torpedo steer the usual substantially straight course for approximately 10,000 yards and thereupon to steer a circular course, whereby the chance of its doing execution upon some one 20 of the enemy ships is greatly increased. Heretofore, the torpedo being aimed to steer a straight course, has had only one chance or opportunity for hitting its target; if it missed the target it would continue to travel in the same direction and unless some other ship chanced to be in its line of travel beyond, the torpedo shot was wasted. But, 25 by causing the torpedo to steer a circular course in the zone or region occupied by the enemy ships, its chance of hitting one or more ships is greatly increased.

This desideratum has been heretofore 30 recognized and means have been proposed for accomplishing this result, but such means have not been such as to render them practicable in view of the exigencies of warfare. The present invention provides improved means for accomplishing the object 35 above stated, being such as to render the performance of the torpedo more certain and to facilitate its accurate adjustment to the desired course.

According to the present invention, instead of providing means extraneous to the 40 normal steering mechanism for locking the rudder when hard over to either side, or otherwise dominating the steering function 45 so as to force the torpedo to steer a curved

course, the steering mechanism is so modified and controlled as to first function in its normal manner until a predetermined range is reached, and thereupon to accomplish the steering of the circular course for 60 the remainder of the run of the torpedo. This may be variously accomplished, a suitable means therefor being herewith illustrated.

Figure 1 of the accompanying drawings is a diagram showing the course of the 65 torpedo;

Fig. 2 is a vertical section of the after portion of the torpedo, illustrating the application of the present invention;

Fig. 3 is a transverse section thereof looking aft, the section being in the plane of the line 3-3 in Fig. 2;

Fig. 4 is a plan of part of the steering mechanism on a larger scale, partly in horizontal, longitudinal mid-section;

Fig. 5 is a side elevation of the same mechanism, partly in vertical mid-section;

Fig. 6 is an enlargement of part of Fig. 3, being partly in vertical transverse section;

Fig. 7 is an enlargement of the cam wheel 80 and connections shown in Fig. 2, with the air valve in longitudinal mid-section;

Fig. 8 is an elevation of the setting scale on the outside of the torpedo hull.

Referring first to Fig. 1, A designates a 85 launching tube and B designates the course of a torpedo launched therefrom. The figures 4,000, 10,000 and 15,000 marked on this course may be taken as indicating yards or meters. B¹ indicates (to a magnified scale) 90 a circular course which may be steered by the torpedo, which in this case commences at 4,000 yards. B² in dotted lines indicates a similar circular course which may commence at 1000 yards. These figures are 95 given as illustrations, since the circular course may begin at any point after a suitable interval in the run of the torpedo sufficient to carry it far enough away from the point of launching to avoid danger to the 100 torpedo boat from which it is launched, or other vessels of the same fleet. In the illustration given, 15,000 yards is assumed as the total normal straight run of the torpedo. The full lines show the launching of the 105 torpedo in the normal manner by aiming the launching tube at the target. The diagram shows in dotted lines at the left, the case of the so-called "angle fire" in which the torpedo tube, indicated at A', is aimed in a 110

direction removed by a given number of degrees from the ultimate straight course B of the torpedo, the steering mechanism being set to steer through the circular arc indicated at α , which continues until the torpedo has been steered through an arc of the prescribed number of degrees, whereupon the steering mechanism is released in a well-known manner and thereupon functions normally to steer the torpedo on its straight course B. In referring to B as a straight course it is understood that this term is used in a general sense, since the steering apparatus used in torpedoes actually steers a slightly sinuous course, veering alternately to opposite sides of the line of aim, the rudder being thrown alternately to port and starboard in the normal functioning of the gyroscopically-controlled steering mechanism. The course shown at B in the diagram is therefore the general course steered, being the mean of the successive arcs or sinuosities, which would be imperceptible in a diagram on the scale here given.

25 The object of the present invention is to provide such construction of steering mechanism as will enable the torpedo to be launched in the normal manner either for direct fire or angle fire, and to provide that after it has traversed a minimum portion of its course (here assumed to be 4000 yards) it may be caused thereafter, at any desired point in the run, to abandon its normal straight course and steer a circular course such as shown at B^1 or B^2 . The point in the course at which the circular steering begins is determined by the actual or estimated distance of the target, so that the circular course steered by the torpedo shall coincide as nearly as possible with the location or course of the enemy ship or fleet and enable the torpedo to repeatedly traverse such course, thereby correspondingly multiplying its chance of doing execution.

50 Referring to Fig. 2, C designates the propeller shaft or shafts for driving in the usual manner the propeller screws which turn in contrary directions. D designates, as a whole, the usual gyroscopic steering mechanism, which comprises a steering engine E (or any other equivalent steering mechanism) which, through the usual actuating rod or tiller rod b operates the tiller c for turning the rudders d . Compressed air from the air flask passes through a pipe f to a pressure-reducing valve g , and thence at reduced pressure by pipe h to the usual superheater F, and thence by pipe i to the engine, which latter (not shown) may be a reciprocating engine or turbine, as preferred. The engine drives in the usual manner the propeller shaft C. All of the parts thus far referred to are customary in torpedoes and may be of the usual or any suit-

able construction, and form no part of the present invention.

The present invention requires first some suitable form of timing or reducing mechanism for bringing about the initiation of the steering of the circular course at any desired point in the run of the torpedo, and so that this period may be determined by the operator before the launching of the torpedo. In the construction shown, the timing mechanism consists simply of a train of gearing (in the specific form shown comprising a worm 4 on the propeller shaft C, a worm-wheel 5 driven thereby carrying on its shaft a worm 6 which in turn drives a worm-wheel 7 on the shaft of which is a worm 8 which drives a worm-wheel 9), this train terminating in a revolving cam G having a cam projection or tooth j which at the predetermined point in its revolution actuates the mechanism for determining the circular steering.

For accomplishing the circle steering according to this invention, it is essential to terminate the normal steering operation (whereby at repeated intervals the rudder is thrown alternately to port and starboard) and to so operate on the tiller as to throw the rudder to one side and hold it there during the period of steering such circular course. Obviously, this result may be accomplished in various ways, as, for example, by discontinuing the alternate movements of the steering engine or by so dominating the latter that its continued alternate movements or efforts are impotent to throw the rudder. A simple and easily applied means for accomplishing the desired result is that shown in the accompanying drawings, which involves the application of mechanical means for holding the tiller when thrown to one side and preventing its being afterward operated or thrown back by the action of the steering engine. This means is very simple in its application and involves no interference with the normal operation of the steering engine under attempted control of the gyroscope, and hence involves no change in the construction of the steering engine or gyroscopic steering mechanism. The circle steering means therefore simply dominates and overcomes the normal action of the steering mechanism, and forcibly holds the rudder hard over (or partially so) to either side so as to steer a circular course in the corresponding direction.

While this result may be accomplished by the application of various mechanical means, the simplest, most easily controlled, and most positive and effective in its operation is by means operated by compressed air. To this end a special air valve is provided which is operated by the cam projection j to admit the air at the proper instant to exert its dominating effect to overcome the normal

steering. The preferred construction of this apparatus will now be described.

The air valve H receives air at reduced pressure from the low pressure side of the 5 reducer g through a pipe k. This valve is normally closed, but when opened by the cam j it admits compressed air through a pipe l to a compressed air cylinder J which is suitably mounted in any convenient location within the torpedo. The piston J' of 10 this cylinder is normally retracted by the spring m. Its piston rod carries the effective circle steering element K which is to act directly or indirectly upon the tiller e. In 15 the construction shown the element K is a wedge, preferably a double or bifurcated wedge, which embraces the tiller rod b and, when projected from its normal position to its active position (shown in full lines in 20 Fig. 5) acts upon a collar or projection n on said rod and thrusts this collar in one direction or the other to thereby throw over the rudder. The air pressure engine J is made to dominate the steering engine E, 25 either by making it of larger area or in any other convenient manner. The wedge member K is shown as supported against a fixed support p which receives the reaction of the wedging thrust.

30 The air valve H is specially constructed to avoid any derangement due to leakage. The valve casing q incloses a chamber r to which compressed air is constantly admitted through the port k'; the outlet through port 35 l' is closed by a diaphragm s of thin metal or other puncturable material which, under the operation of the cam projection j, is punctured by means of a spur t carried by a plunger u which is normally retracted by 40 a spring u'. The escape of air around the plunger u is prevented by a packing v which is held seated in the inactive condition of the valve. The diaphragm s is carried by a removable member q' of the valve casing, 45 which is shown as a screw plug, the diaphragm being preferably soldered thereto. It results that the compressed air is reliably sealed off by the diaphragm from access to the pipe l and engine J until the spur is 50 operated to puncture this diaphragm, whereupon the compressed air rushes through and operates the engine J; and thereafter the engine J is held in the position shown in Fig. 5 by the continued action of the compressed air. The described construction of 55 air valve H affords an important safeguard against premature operation of the circle steering mechanism by preventing any possibility of leakage of compressed air into the 60 cylinder J.

To enable the operator to determine at what point in the run of the torpedo the circle steering shall begin, the timing mechanism is made adjustable at will. A simple 65 way of accomplishing this is to provide that

the cam G may be turned at the outset to any desired position so as to cause its cam projection j to traverse any required part of its circular course before acting upon the valve stem u. To this end the timing mechanism is 70 so proportioned that the cam G will execute not over one complete revolution during the entire maximum course of the torpedo. If this course is 15,000 yards, for example, the gear 9 carrying the cam G may be proportioned to execute one revolution in 15,000, or somewhat over 15,000 yards. If the circle steering is commenced at, say, 4,000 yards, the cam G has to be set initially to bring its projection j to a corresponding fraction of 75 the total circular movement in advance of the operative movement of the stem u; if the circle steering is to begin at any later point in the course, the cam has to be set that much farther back. Such setting is accomplished 80 by the operator before launching the torpedo and is determined by aid of a scale marked on the exterior. The operator has first to disconnect the cam with the gear 9, then turn it to the required position, and 85 then re-connect it with this gear. For accomplishing this the means best shown in Figs. 6, 7 and 8 are provided.

The cam G is connected to a spindle w which passes out through a fitting x in the 95 hull of the torpedo and has on its outer end a head w' which has a square socket or is otherwise shaped to be engaged by a key or wrench for turning it and also for drawing it back to the position shown in Fig. 100 6. When so drawn back it pulls the cam G out of its normal position and withdraws a pin 10 carried by the cam from one of a series of holes 11 formed in the gear 9. These holes are spaced apart a distance corresponding, for example, to 1000 yards in the run of the torpedo, or any other convenient spacing. In this withdrawn position the cam may be turned by turning the head w' until it is brought to the required 105 110 position. This is determined by a pointer y on the head w' which traverses a circular graduated scale z (Fig. 8) which is marked on the rim of the fitting x. On this scale the zone z', shown in black in Fig. 8, is 115 120 that portion under, for example, 4000 yards, within which it is unsafe to start the circle steering and which may be deemed, therefore, a forbidden zone. Beyond this it may be set to any point between 4,000 yards and 15,000 yards. When turned to this position, the operator then pushes back the head w' and thereby restores the cam G to its normal position, its pin entering the corresponding one of the holes 11 which it 125 finds alined with it. Thus, by a very quick and simple operation which may be performed at any time before the launching of the torpedo, the operator determines at what point in its straight course it shall de- 130

part therefrom and begin steering a circular course.

It is to be observed that the present invention avoids the application of any accessory devices to the exterior of the torpedo, avoids the carrying of any impedimenta by the rudders *d*, and provides mechanism which is wholly housed within the torpedo and acts upon the rudders through the medium of their tiller. Further, the mechanism is constructed to operate with the utmost precision and certainty. It is of such construction that it can by no possibility interfere with the normal steering operation in case circle steering is not desired, and so that when set for circle steering the latter cannot begin prematurely.

What I claim is:—

1. In a torpedo comprising propelling and automatic steering mechanism, means for causing the torpedo, after traversing a predetermined fraction of its normal run, to then steer a curved course, such means comprising a timing device for bringing it into action at a determined point in the run of the torpedo, and a controlling means for holding the rudder to one side.

2. In a torpedo according to claim 1, the controlling means adapted to stop the steering action of the normal steering mechanism, whereby to hold the rudder to one side.

3. In a torpedo according to claim 1, the controlling means adapted to dominate and overcome the normal steering action of the steering mechanism and thereby to hold the rudder to one side.

4. In a torpedo according to claim 1, the controlling means pneumatically operated.

40 5. In a torpedo according to claim 1, the controlling means comprising a compressed air engine, with an air valve operated from the timing device to operate said engine.

6. In a torpedo according to claims 1 and 45 5, said compressed air engine adapted to dominate and prevent the operation of the normal steering mechanism.

7. In a torpedo according to claim 1, said controlling means comprising a mechanical device acting between the steering mechanism and tiller.

8. In a torpedo according to claim 1, said controlling means comprising a reciprocating part having a wedge action adapted to 55 throw the tiller to one side.

9. In a torpedo according to claim 1, such timing device comprising a reducing train

driving a terminal member, the latter adapted for angular displacement relatively to the train whereby to determine at what 60 point in the run of the torpedo it shall act.

10. In a torpedo according to claims 1 and 9, the terminal member of said timing device being a rotatably adjustable cam.

11. In a torpedo according to claim 9, 65 means for axially displacing the terminal member whereby to vary its rotative engagement with the train.

12. In a torpedo according to claim 9, an indicating means on the exterior of the 70 torpedo for ascertaining the angular arrangement of the terminal member.

13. In a torpedo according to claim 1, said controlling means being pneumatically actuated under control of a valve operated 75 by the timing device, such valve comprising a puncturable sealing means and a device for puncturing such sealing means.

14. In a torpedo according to claim 13, such valve comprising a thin diaphragm and 80 a reciprocating plunger carrying a spur for puncturing such diaphragm.

15. In a torpedo according to claim 14, said valve plunger having a stem passing out through its casing and a packing for 85 preventing leakage around said stem, and a spring holding said plunger normally retracted with said packing seated.

16. A torpedo comprising means to alter its movement, fluid operated means to control the said movement altering means, and means to render said fluid operated means inoperative and to actuate said movement altering means, substantially as specified.

17. A torpedo comprising a rudder, an 95 actuating rod operatively connected to said rudder, fluid operated means to control the movement of said actuating rod, and means to render said fluid operated means inoperative and to move said actuating rod, substantially as specified.

18. A torpedo comprising propelling means, a rudder, an actuating rod operatively connected to said rudder, fluid operated means to control the movement of 105 said actuating rod, and means controlled by said propelling means to render said fluid operated means inoperative and to move said actuating rod, substantially as specified.

In witness whereof, I have hereunto signed my name.

WILLIAM DIETER.
